[57] ABSTRACT

The clamp holds the intake passage of a dust bag to the outer periphery of the exhaust passage of an air filter or the like, and consists of an elongated strip of spring metal having a central part which surrounds the aperture of the dust bag and intake, an integrally formed arcuate piece at one end of the strip which terminates in an open loop, and an eye adjacent the other end of the strip in which one arm of a wire lock form is pivotally mounted. When the strip is brought about the filter bag and intake the second arm of the wire lock form is put into the open loop and the wire form is moved to over center position to lock the strip in place.

FILTER BAG CLAMP

DESCRIPTION OF THE DRAWINGS

FIG. 1 is a side elevational view of the clamp provided by the invention, before being used;

FIG. 2 is a view showing the clamp in position ready to attach a dust bag to the intake of an air filter, before being locked;

FIG. 3 is a perspective view of the parts shown in FIG. 2, but shows the clamp after being locked, and

FIG. 4 is a side elevational view of a modified form of clamp, also according to the invention.

DESCRIPTION OF THE INVENTION

The invention provides a clamping device of new and improved construction and operation which is particularly useful in clamping the aperture of a dust bag about the circular discharge passage of an air filter. The improved clamp is unitary in construction and may be easily and cheaply made, and is simple to install and remove.

A preferred form of the clamp is disclosed in FIG. 1 of the drawings and comprises an elongated strip of spring steel of sufficient length to more than surround the cylindrical discharge passage of an air filter with the aperture of a dust bag closely surrounding the passage. The strip is of sufficient width to engage the dust bag and discharge passage over a substantial area and comprises a central part 2, and end part 4,6, the central part 2 being substantially straight and un-interrupted.

Adjacent its one end 6 the strip is formed into arcuate shape, which may be substantially semicircular, and at its free end this arcuate part is bent back upon itself toward the main body of the strip to form a loop 8 having an open entrance 10.

Adjacent the other end 4 of the strip, at a point substantially removed from the free end thereof, there is provided an eyelet 12 the axis of which extends transversely of the strip. The eyelet is provided on the same side of the strip toward which the arcuate 6 is bent and, in the form of invention disclosed in FIG. 1, the eyelet is formed from a separate piece of flat spring metal 14 which is welded to the strip. The remainder of the strip, being the part between the eyelet 12 and the free end of the strip part 4, is arcuately curved in a direction away from the side of the strip to which the eyelet 12 is attached.

A handle member designated generally by numeral 20 is provided and is formed of bent wire having two parallel arms 22, 24 connected at their ends by parts 26, 28, the latter being extended beyond arm 22 to provide a handle part 30. The arm 24, which is the one most removed from the handle part 30, is pivotally received within the eyelet 12 and the handle normally hangs loosely therefrom.

The use and operation of the clamping device is illustrated in FIGS. 2 and 3, and it will be seen that when it is desired to clamp the aperture 40 of a dust bag 42 about the cylindrical exhaust passage 44 of an air filter the aperture is first put into surrounding relation with the passage as shown in the drawings. The surface of the strip opposite to that to which the eyelet is attached is then placed in surface-to-surface relation to the exterior of the dust bag aperture and the strip is then bent around the dust bag and exhaust aperture and the open loop 8 at the one end of the strip is hooked over arm 22 of the handle with the free end part 4 of the strip lying beneath the other parts of the strip. The handle is then operated to overcenter position by rotating it about its pivotal connection to eyelet 12, thus releasably locking the parts in the position shown in FIG. 3.

A second embodiment which the strip may take is disclosed in FIG. 4 and in this embodiment the eyelet 12 is formed from the strip itself rather than in a piece welded to the strip.

In any form which the clamping device provided by the invention may take the distance from the center axis of the eyelet 12 to the adjacent surface of the strip itself is important as it is this distance which insures that the handle member will remain in overcenter locked position, as in this locked position the arm 24 of the handle member must be farther away from the adjacent surface of the strip than the arm 22 of the handle member.

The arcuate part 6 of the clamp provides spring action which absorbs any variation in the size of the assembled filter aperture and dust bag, while the curved end part 4 and the location of the eyelet 12 enables the manufacturer of the clamp to absorb all manufacturing tolerances by location of the eyelet.

I claim:

1. A device for encircling and releasably connecting two concentric annular members in abutting relation, comprising an elongated flat strip of flexible metal, a loop at one end of the strip which has an open entrance at one side of the strip, an eyelet adjacent the other end of the strip and on the other side thereof from the loop, the eyelet and the loop having parallel axes which extend at right angles to the length of the strip, a snap-over locking device comprising an open rectangular member formed of bent wire having parallel end parts connected at their ends by side parts, one of the side parts being extended beyond a first one of the end parts to form a handle and the other end part being pivotally received in the eyelet, whereby when the strip is bent with the eyelet on the outside and the said first one of the end parts of the locking device is received within the loop the locking device may be rotated by the handle about the eyelet to overcenter position to releasably connect the ends of the strip.
